UNITED STATES PATENT OFFICE.

NORMAN E. GEE, OF ALTOONA, PENNSYLVANIA.

LOCOMOTIVE-STOKER.

1,103,406.

Specification of Letters Patent. Patented July 14, 1914.

Application filed October 15, 1912. Serial No. 725,960.

To all whom it may concern:

Be it known that I, NORMAN E. GEE, a citizen of the United States, residing at Altoona, in the county of Blair and State of Pennsylvania, have invented certain new and useful Improvements in Locomotive-Stokers, of which the following is a specification.

The present invention relates to certain new and useful improvements in mechanical stokers such as are adapted to be employed upon steam locomotives, the object of the invention being to provide a device of this character which embodies novel features of construction whereby it will operate in an effective and satisfactory manner to convey the fuel from the magazine of the tender and discharge it into the fire box of the engine.

A further object of the invention is to provide a mechanical stoker which is provided with a novel selective fuel feed which admits of the location of the fuel feeding position on the grate being selected at the will of the fireman, thereby enabling an even depth of fire to be maintained over the surface of the furnace grate at all times regardless of the working conditions of the locomotive.

Another object of the invention is to provide a locomotive stoker which is adapted to feed various kinds of coal over the fire, thus enabling the use of the maximum size of grate for the furnace, while at the same time the delivery chute of the stoker occupies such a position as not to interfere with hand firing when such is necessary.

The invention also aims to provide a mechanical stoker which will use all kinds of "run of mine" coal without danger of becoming clogged when the coal is coarse or feeding too freely when the coal is fine.

With these and many other objects in view, which will be readily apparent to steam and railroad engineers, the invention consists in the novel construction, combination and arrangement of parts as will be hereinafter more fully described, illustrated and claimed.

The essential features of the invention in carrying out the objects above indicated are necessarily susceptible to a wide range of structural modifications without departing from the scope of the appended claims or the spirit of the invention, but a preferred em-

bodiment thereof is shown in the accompanying drawings, in which:

Figure 1 is a rear elevation of a portion of a standard locomotive which is equipped with the mechanical stoker, the conveyer trough being shown in section, and portions of the locomotive equipment being shown for the purpose of illustrating the relation of the stoker to the standard locomotive. Fig. 2 is a longitudinal sectional view of a portion of the rear of a locomotive furnace, the connection between the engine and the tender, together with a longitudinal sectional view of the forward end of the tender, showing clearly the manner of mounting the mechanical stoker upon the standard engine and tender. Fig. 3 is a skeletonized longitudinal sectional view of the coal crusher, coal-conveyer, and elevating chute, together with a portion of the fire door, fire box, and grate. Fig. 4 is an enlarged front view of the coal delivery chute with the deflector plate in position. Fig. 5 is a plan view of the coal delivery chute, the bottom deflector plate being shown in position. Fig. 6 is a transverse sectional view through the coal delivery chute on the line 9—9 of Fig. 5. Fig. 7 is a similar view on the line 11—11 of Fig. 5. Fig. 8 is a diagrammatic view of the general combination of instrumentalities including a stocking or delivery chute, the driving engine, the steam intercepting valve, and the fireman's selective valve. Fig. 9 is a sectional view through the steam intercepting valve, showing the piston valve member in a different position from that shown by Fig. 8. Fig. 10 is a detail view of the rotary valve plug of the fireman's controlling valve.

Corresponding and like parts are referred to in the following description and indicated in all the views of the drawing by the same reference characters.

The present design of mechanical stoker contemplates a series of related elements which work in unison to crush the coal, convey the same to the fire box, and force it into the furnace of the locomotive, and in carrying out the present invention no change is necessary in the standard design of locomotive, fire box, or grates in the locomotive furnace. The area of the grate is thus not diminished by the installation of the stoker, and it follows that a locomotive furnace

equipped with the present stoker will not necessitate the forcing of the fires up and above that which is necessary with the same size locomotive furnace not equipped with the stoker.

- For the purpose of illustration, the stoker is shown as applied to a locomotive A and tender B of standard design. (See Fig. 2.) The fuel is delivered through the bottom of the tender magazine 40 to the coal crusher 23, and from this crusher the coal is carried forwardly under the deck plate of the locomotive by means of the conveyer 35. From the forward end of the conveyer 35, the coal is received in an elevator chute 75 and carried upwardly through the locomotive deck plate to the delivery chute 85, from the mouth of which it is discharged into selected portions of the fire box.
- The numeral 10 designates the driving engine, which is secured to the locomotive frame 11, and may receive steam from the bridge pipe of the locomotive, the steam dome, or from any other suitable source as may be found desirable. A piston 117 is mounted to reciprocate back and forth within the cylinder of the driving engine, the said piston being connected to a piston rod 12 which projects forwardly therefrom and is pivotally connected at 13 to the lower end of a crank arm or lever 14 which projects downwardly from the rock shaft 16 and is rigid with the said rock shaft. This rock shaft 16 is journaled within the suitable bearings 18 and 19 and is provided with a pair of upwardly extending levers or crank arms, 20 and 21. (See Figs. 1 and 2.) The forward ends of the crusher operating rods 22 are pivotally connected at 28 to the respective arms 20 and 21 at points spaced from the upper end thereof, the rear ends of the said members 22 being connected to the crusher. The detail structural characteristics and functions of this crusher form no part of the present invention and are not claimed herein, and therefore a detailed description thereof will be unnecessary.
- For the purpose of increasing or decreasing the supply of coal from the tender magazine to the crusher, there is provided a supply control plate 43, the said plate 43 being mounted to move in longitudinal guides 44 provided at the upper portion of the crusher frame or casting 34. The end of this plate 43 is pivotally connected to the upper ends of a pair of levers 45, the said levers projecting upwardly from opposite ends of a shaft 46 and being rigid therewith. This shaft 46 is shown as journaled in suitable bearings 46^a which are applied to the rear end of the conveyer 35. One of the levers 45 is connected by a forwardly extending rod 47 to the usual shaker grate lever 48, which is a part of the standard equipment for every steam locomotive. (See Fig. 1.) This fuel

supply control plate 43 can be adjusted to regulate the flow of the coal or fuel from the tender magazine 40 to the crusher 23, and the feeding of the coal can thus be regulated at the will of the operator.

The coal conveyer, designated in its entirety by the numeral 35, is preferably of the construction, shown in Fig. 3, of the drawings. While the details of construction of the coal conveyer, and its immediately associated parts, are not claimed herein as a part of the present invention, it will be necessary to briefly refer thereto in order that a clear understanding may be had of the manner of advancing the fuel into the delivery chute where the steam jets come into play to eject the charges into the fire box, and accordingly reference will now be made to this conveyer. The conveyer trough is shown as constructed of side plates 55 and a bottom plate 56, reinforcing angles 57 being provided for securing the bottom plate to the side plates. The top of the conveyer is provided upon opposite sides thereof with the longitudinal guides 58 within which the conveyer bars 59 are slidably mounted, the said conveyer bars being held in a properly spaced relation by means of the transversely disposed finger supporting rods 60 which connect the same. A series of coal conveyer fingers 61 is pendent from and pivotally mounted upon each of the transverse rods 60, each of the said fingers 61 being formed with a rearwardly extending web portion 62 which is provided at the top thereof with a shoulder 64 adapted to engage the transverse stop bars 65 to limit the rearward swinging movements of the conveyer fingers, although the said conveyer fingers are perfectly free to swing forwardly. The stops 65 may be in the nature of bars which have the ends thereof bent laterally to provide feet 66 adapted to be secured by suitable fastening members 67 to the reciprocating conveyer bars 59. The top flanges 68 of the longitudinal guides 58 hold the conveyer bars 59 securely against upward movement, although the said conveyer bars are perfectly free to reciprocate back and forth longitudinally.

The forward ends of the conveyer bars 59 are connected to a cross head 70, the ends of the cross head being engaged by the links 73 which connect the same to the upper extremities of the respective arms 20 and 21 projecting upwardly from the rock shaft 16. It will thus be obvious that as the piston 117 of the engine 10 is reciprocated back and forth by the admission of steam thereto, the rock shaft 16 will be operated and motion transmitted from the rock shaft to the crusher and to the conveyer. Upon rearward movement of the conveyer slides 59, the fingers 61 will swing forwardly and upwardly and slip over the coal within the

conveyer trough. However, upon the forward movement of the conveyer slides or bars 59, the fingers 61 will be projected downwardly into the coal and will engage the coal to move it forward within the conveyer trough, owing to the fact that any rearward swinging movement of the fingers 61 is rendered impossible by reason of the engagement of the shoulders 64 with the stop bars 65.

At this point attention may be directed to the fact that the movement of the crusher head is different from that of the coal conveying fingers, owing to the fact that the crusher operating rods 22 and the conveyer operating rods or links 73 are connected to the levers or arms 20 and 21 at different points in the length thereof. The crusher head has the greater leverage and smaller amount of movement, this difference in movement being usually necessary in order to keep the conveyer clear from coal accumulations.

The conveyer 35 extends forwardly under the usual deck plate D of the locomotive, the forward end of the conveyer being loosely connected by means of the ball and socket joint 127 to the locomotive frame, while the rear end of the conveyer is supported upon the rollers 128 so as to have a limited back and forth movement. It will be remembered that the crusher 23 was also loosely connected to the bottom of the tender magazine, and by means of these loose connections sufficient freedom of movement is provided to compensate for the numerous relative movements between the locomotive and tender.

From the forward end of the conveyer 35, the fuel is discharged into the elevator chute 75 which carries it up to the delivery chute 85. An auxiliary conveyer mechanism is mounted within the elevator chute 75 for the purpose of producing a positive upward feeding of the coal within the same.

The interior of the elevator chute 75 is provided upon opposite sides thereof with the endless guideways 150 which have substantially the shape of a parallelogram, the long sides thereof being spaced from and parallel to the bottom of the elevator chute, while the short sides thereof are inclined forwardly and downwardly toward the delivery chute. The conveyer fingers 76 of this auxiliary mechanism are pivotally mounted upon the rods 77 which extend transversely between and connect the conveyer bars 18, the said conveyer bars having the rear ends thereof pivotally connected to the cross head 70 so as to receive motion therefrom. The extremities of the transverse rod 77 at the forward end of the conveyer bars 18 project laterally beyond the conveyer bars and are loosely received within the endless guides 150. A spring detent 151 is provided to-

ward the forward end of the lower side of each of the endless guideways, the nose of the spring detent having the rear face thereof beveled or inclined so that upon the forward movement of the auxiliary conveyer 70 fingers 76 the extremities of the rod 77 will force the detents 151 inwardly and pass beyond the detents. Upon the rearward movement of the conveyer mechanism, the spring detents 151 will engage the extremities of

75 the rod 77 and cause the same to travel upwardly through the inclined forward ends of the guideways 150. The fingers 76 will thus be bodily raised and moved away from the bottom of the elevator chute 75. Upon the forward movement of the conveyer elements the extremities of the rod 77 will be caused by gravity to travel downwardly and forwardly so as to force the conveyer fingers 76 downwardly into the coal and cause them 85 to produce a positive forward movement of the coal through the elevator chute. It will thus be obvious that upon the forward movement of the conveyer elements the ends of the rod 77 travel in the lower sides of the 90 cam guideways 150 so as to force the conveyer fingers 76 downwardly into the coal, while upon the rearward or downward movement of the conveyer elements, the ends of the rod 77 travel in the upper sides of the 95 cam guideways 150 so as to lift the conveyer fingers 76 bodily away from the coal. It will further be observed that the conveyer fingers 76, as in the previous instance are pivotally mounted upon the transverse rod 100 105 77 so as to swing forwardly upon the rearward movement of the conveyer elements, although upon the forward movement of the conveyer elements, the rearward swinging movement of the fingers 76 is limited by reason of the engagement of the shoulders 76^a with the transverse stop bars 76^b. In order to prevent the fuel from slipping downwardly within the elevator chute 75 upon the rearward movement of the conveyer elements, the bottom of the said elevator chute 75 is shown as provided with a series of 110 forwardly facing shoulders 152.

From the upper end of the elevator chute 75 the coal passes into the delivery chute 115 85, from which it can be discharged by selective means into the required or desired areas of the fire box. This delivery chute 85 is provided at the top thereof with the steam nozzle 87, and at the respective sides 120 thereof with the inclined nozzles 88 and 89, the said nozzles being forwardly disposed so that jets of steam from the same will strike against and impinge upon coal within the said chute and carry it into required portions of the fire box. A pair of side deflecting wings 90 are hinged to opposite sides of the delivery chute 85, while a bottom deflector plate 100 is hinged to 125 the bottom of the delivery chute 85. This 130

deflector plate 100 (see Fig. 2) has a limited up and down swinging movement and has an operative connection such as indicated at 130^a with a controlling lever 130. This lever 130 is provided with the usual latch 131 which is adapted to engage a segmental rack 129 to admit of the lever and bottom deflector plate 100 being set in an adjusted position. The upper or top surface of the deflector plate 100 (see Fig. 5) is provided with the raised portions or ribs 102 having the laterally curved side surfaces, 101. Channels 99 are provided between the raised portions 102, and a transverse series of jet opening 98 at the mouth of chute 85 are arranged to discharge jets of steam into the channels for the purpose of sweeping the fine coal from the deflector plate. The laterally curved surfaces 101 cause the fine coal to be deposited at the rear of the fire box, this feature having been found necessary and quite essential in order to obviate the escape of thick black smoke from the stack. In this connection it may be noted that engineers have learned through exhaustive experiments that the smoke nuisance can be materially abated by not letting the fine coal get into the furnace where the force of the draft will pick it up and carry it through the flues before it is burned. The jet openings 98 are adapted to receive steam through a duct 97 in the bottom of the delivery chute 85, the said duct communicating with a pipe 96.

35 The curved surfaces 101 are the sides of the upstanding ribs 102 which form sort of a screen or filter for the coal, the larger portions of coal resting on the top portions of the ribs 102 and being readily caught by the force of the escaping steam from the nozzles 87, 88 and 89 and carried forward into the fire box. The position of the coal as it strikes the grate is determined by the fireman through the adjustment of the deflecting wings 90, together with the coöperation of the fireman's controlling valve which is designated in its entirety by the numerals 103.

50 The two side wings 90 are connected by a link 91 so as to move in unison, and any suitable actuating member such as the slide 92 may be employed for setting these wings in an adjusted position. It will be obvious that when the lateral wings 90 are both swung in the same direction to one side, the tendency of the stoker will be to feed the coal to one side of the grate and blank the opposite side of the grate, while when the lateral wings project straight forward, the tendency of the stoker will be to feed straight ahead.

55 The fireman's controlling valve 103 includes a hollow rotary plug 104 which is provided with a series of lateral openings 106. A handle 153 is provided for turning

the plug 104, and any suitable indicating means may be provided in connection with this handle for enabling the operator to admit steam to selected ones of the steam nozzles, according to the part of the fire box it may be desired to supply with fresh fuel. Steam pipes 107 lead from the respective nozzles 87, 88 and 89, while a steam pipe 96 leads from the duct 97. These pipes 96 and 107 communicate with openings or ports 106^a in the casing of the valve 103. A steam supply pipe 107^a communicates with a duct 105 in the casing of the valve 103 and steam is admitted through this duct and one of the openings 106 of the valve 80 plug 104 into the interior of the said valve plug. By suitably rotating this valve plug 104, selected ones of the ports or openings 106 therein can be brought into register with the ports 106^a of the valve casing so as to 85 place certain selected nozzles in communication with the source of steam supply. The supply of steam to the fireman's controlling valve and to the nozzles is intermittent, so that the jets of steam act successively upon the fuel with a piston action. It will thus be seen that this part of the stoker acts as a stoking engine, the intermittent jets of steam impinging upon the coal at successive intervals of time so that the steam jets 95 form in effect piston members which engage the coal and shove it into the fire box. It will be readily obvious that by properly adjusting the controlling valve 103, the fuel can be supplied to any desired part of the 100 furnace grate at the will of the operator, and this selective feeding of the fuel is placed more completely under the control of the operator and rendered more effective when the lateral wings 90 are used in conjunction with the fireman's controlling 105 valve. As has been previously explained, the sweeping jets 98 serve to act upon the fine coal which may have been detained upon the bottom of the deflector plate 100 110 so as to cause the same to be deposited in the rear of the fire box.

The steam for the jets of the delivery chute is supplied by the exhaust from the main engine 10, an intercepting valve 108 115 being provided for causing the steam to reach the jets in intermittent streams. This valve 108 is provided with a substantially cylindrical chamber 110 within which a two diameter piston valve 110^a is accurately 120 mounted for a reciprocating movement. This valve member 110^a is provided with a transverse passage or port *b*, and also with a transverse passage 112. When the valve member 110^a is in the position illustrated 125 by Fig. 8, exhaust steam from the engine 10 passes through the exhaust pipe E to the duct 111^a of the valve 108, flows through the transverse port *b* of the valve member 110^a, and from thence passes through the port 111 130.

to the pipe 107^a which leads to the fireman's controlling valve 103. As the steam passes through the transverse port *b* of the valve 110^a, it will also flow through the longitudinal passage 113 of the said valve and issue slowly through the small port 114 into the space between the end of the valve 110^a and the closed end of the valve casing. This steam will act upon the valve member and force the same to the left, until the position indicated by Fig. 9 is finally reached. The steam within the closed end of the valve casing can then escape through the opening 116 into the passage 112^a which communicates with the pipe 155 leading to the smoke box. When the valve 110^a is in the position illustrated by Fig. 9, the supply of steam through the pipe 107^a to the fireman's controlling valve 103 is completely shut off, the exhaust steam from the exhaust pipe E passing through the duct 111^a, transverse port 112 of the valve member 110^a, and the passage 112^a to the pipe 155 which carries it to the smoke box.

The piston 117 of the engine 10 being at the forward end of the stroke, live steam entering the chamber 119 of the cylinder of the engine at 118, will also enter the pipe 120, flow through one of a pair of U shaped passages 121 in the small end of the valve member 110^a, and enter the opposite end of the casing of the valve 108 so that the expansive action thereon will force the valve member 110^a back into the position shown by Fig. 8. A further supply of steam will then be admitted to the fireman's controlling valve 103 and the valve member 110^a again forced back to the position shown by Fig. 9, by reason of the slight leakage of steam through the port 114 into the space between the end of the valve member and the closed end of the valve casing. With the piston 117 at the rear end of its stroke, steam entering the chamber 123 of the cylinder will also flow through the pipe 124 and through the curved passage 122 of the small end of the valve member 110^a so as to enter the interior 110 of the casing 108 through the other of said passages 121 and again act upon the valve member 110^a to force it back to the position shown by Fig. 8. When the valve member 110^a reaches the extreme position indicated by Fig. 8, the steam in the forward end of the space 110 can exhaust through the port 110^b into the port 111 and be siphoned away by the steam flowing through the pipe 107^a. It will thus be obvious that the exhaust from the engine 10 will be alternately supplied to the fireman's control valve 103 and to the pipe 155 leading to the smoke box. The intercepting valve 108 thus provides an intermittent steam supply for the steam nozzles of the delivery chute, the intermittent jets of steam having a piston action and striking against and im-

pinging upon the coal so as to be very effective in forcing the same into the fire box.

The entire stoker mechanism is actuated either directly or indirectly from the engine 10, and when steam is admitted to this engine, the crusher and all conveyer elements are simultaneously operated, and steam supplied intermittently to the fireman's controlling valve 103. By suitably setting this controlling valve 103, the coal can then be discharged into any desired or selected portions of the fire box so as to maintain an even depth of fire over the entire surface of the locomotive grate at all times, regardless of the working conditions of the locomotive. In this connection, it will be observed that the angular disposition of the inclined nozzles 88 and 89 is such that when either of such nozzles is selected to operate singly, the blast therefrom strikes the fuel obliquely, the result tending to force the same over one end portion of the grate. When the central nozzle 87 is selected for operation singly, the effect is a straightaway blast upon the fuel to discharge the same centrally upon the grate.

Having thus described the invention, what I claim as new and desire to secure by Letters Patent, is:

1. A stoker including a fuel receiver, means for supplying fuel thereto, a plurality of steam jetting nozzles arranged to discharge the fuel from the receiver and arranged at different angles, a source of fluid pressure supply, a single valve in communication with the several nozzles and having means for simultaneously opening one or more nozzles and closing the remaining nozzle or nozzles, and means interposed between said valve and source of fluid pressure supply for producing an intermittent flow of the fluid to and through said valve.

2. A stoker including a fuel receiver, means for feeding fuel thereto, steam jetting nozzles opening into opposite sides of said receiver at an angle for discharging the fuel therefrom, fuel guiding means located beyond the said nozzles and having an adjustment conforming to the angularity of said nozzles, a source of fluid pressure supply for the nozzles, and a variable controlling device having means for selectively controlling said nozzles.

3. A stoking mechanism including a delivery mouth, means for feeding fuel thereto, fuel guiding means including side members, and a bottom plate extending from the discharge end of the mouth, a plurality of sweeping jet openings arranged to produce jets which sweep the top of said bottom plate, a nozzle adapted to produce a fuel injecting jet discharging into the mouth in rear of said fuel guiding means, a source of fluid pressure supply, and a single controlling valve for selectively controlling the

said nozzle and the said sweeping jet openings.

4. A stoker including a delivery mouth, mechanical conveying means for carrying fuel toward the fire box, an engine for operating the conveying means, a nozzle adapted to produce a jet for discharging the fuel from the delivery mouth into the fire box, means for conveying the exhaust from the engine to the said nozzle, and an intercepting valve operated automatically by the exhaust and serving to produce an intermittent feed of the exhaust to the nozzle.

5. A stoker including a delivery mouth, mechanical conveying means for carrying fuel toward the fire box, an engine for operating the conveying means, a nozzle adapted to produce a jet for discharging the fuel from the delivery mouth into the fire box, means for conveying the exhaust from the engine to the said nozzle, and an intercepting valve interposed in the path of the exhaust and the nozzle, said intercepting valve including a reciprocating valve member actuated automatically by the pressure of the exhaust and serving to produce an intermittent feed of the exhaust to the nozzle.

6. A stoker including a delivery mouth, adjustable deflecting wings projecting from the discharge end of the delivery mouth, a swinging bottom plate upon the delivery mouth, sweeping jet openings arranged to produce jets which sweep the bottom plate, a series of nozzles adapted to produce jets for discharging the fuel from the delivery mouth into the fire box, and selective means for controlling the admission of fluid to the nozzles and sweeping jets.

7. A stoker including a delivery mouth, a bottom plate projecting from the discharge end of the delivery mouth and having a plurality of diverging spreading channels therein, a nozzle adapted to produce a jet for discharging the fuel charge from the delivery mouth into the fuel box, means for producing jets to sweep the channels of the bottom plate, a single selective controlling valve in communication with said nozzle and said jets, and a source of fluid pressure supply for the valve.

8. A stoker including a delivery mouth, mechanical conveying means for carrying fuel to the delivery mouth, a series of adjustable deflecting wings at the discharge end of the delivery mouth, a swinging bottom plate projecting from the delivery mouth and having laterally curved channels in the upper face thereof, said channels be-

ing adapted to collect the fine particles of fuel, a series of nozzles adapted to produce jets for discharging the fuel from the delivery mouth into the fire box, means for producing jets which sweep the channels of the before mentioned bottom plate, and selective means for controlling the admission of fluid to the nozzles whereby the nozzles may be caused to coöperate with the deflecting wings to deposit the fuel over the desired areas of the grate.

9. A stoker including a delivery mouth, a plurality of nozzles adapted to produce jets for discharging the fuel from the delivery mouth into the fire box, a source of fluid pressure supply, a controlling valve in communication with the said source of fluid pressure supply, and means for conveying the fluid medium from the controlling valve to the separate nozzles, the said controlling valve enabling selected ones of the nozzles to be operated.

10. A stoker including a delivery mouth, a plurality of nozzles adapted to produce jets for discharging the fuel from the delivery mouth into the fire box, a source of fluid pressure supply, a controlling valve in communication with the separate nozzles and constructed to admit of a selected nozzle or nozzles being operated, means for conveying the fluid pressure from the source of supply to the controlling valve, and means for producing an intermittent flow of the fluid medium from the source of supply to the controlling valve.

11. A stoker including a delivery mouth, a series of nozzles adapted to produce jets for discharging the fuel from the delivery mouth into the fire box, a source of fluid pressure supply, a controlling valve in communication with the source of fluid pressure supply and also in communication with the various nozzles, said controlling valve enabling selected ones of the nozzles to be operated as desired, and an intercepting valve arranged in the path of the fluid medium between the source of supply and the controlling valve, said intercepting valve being operated automatically by the pressure of the fluid medium and serving to produce an intermittent supply of the fluid medium to the controlling valve.

In testimony whereof I affix my signature in presence of two witnesses.
